UNITED STATES PATENT OFFICE.

HANS PETERSEN, OF DAVENPORT, IOWA.

BURNER ATTACHMENT FOR LINOTYPE-MACHINES.

1,205,780.

Specification of Letters Patent. Patented Nov. 21, 1916.

Application filed July 21, 1916. Serial No. 110,597.

To all whom it may concern:

Be it known that I, HANS PETERSEN, citizen of the United States, residing at Davenport, in the county of Scott and State of Iowa, have invented certain new and useful Improvements in Burner Attachments for Linotype-Machines, of which the following is a specification.

The invention relates to improvements in 10 a burner attachment for linotype machines.

It is an object of the invention to provide a simple and efficient vapor burning means for keeping the type metal within the melting pot of a linotype machine in a molten 15 condition. In localities where municipal gas works are accessible, gas burners are employed for this purpose with good results. However, in the operation of linotype machines in the smaller towns difficulty arises in 20 keeping the metal in the proper consistency where no gas works are provided, and various forms of devices for burning gasolene have been utilized with little success for this purpose. One of the most common construc-

25 tions heretofore used consists of a burner adapted to be fed with gaseous vapors positioned beneath the melting pot and having connected therewith a vapor conducting pipe leading up under the throat of the crucible, 30 and having at its end an auxiliary burner, but it has been impossible to get satisfactory results from this structure in view of the fact that the flame is not spread a sufficient distance over the throat of the crucible and 35 the burner is not positioned at the proper point with respect to the mouthpiece of the crucible to maintain the metal passing therethrough in the desired condition to prevent the clogging of the mouthpiece. I am also

40 aware that it has been proposed to provide a separate generator and supply pipe for the main and auxiliary burner, but this structure is objectionable in view of the fact that the vapor passing to the auxiliary burner 45 very frequently condensates during its passage through the conducting tube and prevents the supplying of the proper mixture to the burner underlying the mouthpiece.

It is an object of the present invention to 50 provide a simple gasolene vapor burning attachment for machines of this character consisting of a main fuel burner directly underlying the crucible or melting pot and having a vapor conducting tube extending upwardly therefrom beneath the throat of the pot, to a point near the mouthpiece and

thence out through the side of a jacket surrounding the pot, where a detachable burner is fastened thereto and underlies the mouthpiece of the crucible, this burner together 60 with the main burner keeping the type metal in a molten condition at all times to enable the successful operation of the machine.

A further object of the invention is to provide a heating attachment in which the 65 main heating burner underlying the melting pot is separated from the burner disposed beneath the mouthpiece, that is to say, that the relatively small burner underlying the mouth piece always produces a small steady 70 flame and is not subject to the draft created by the main burner passing beneath the throat of the crucible.

In the drawings, I will illustrate the preferred embodiment of my invention in 75 which—

Figure 1 is a front view. Fig. 2 is a top plan view. Figs. 3-4 are detail views.

Referring now more particularly to the drawings wherein like reference characters 80 indicate corresponding parts, the numeral 1 designates a casing surrounding the melting pot or crucible 2 having disposed therein the usual pump and cylinder 3 communicating with the melting pot and provided with a throat 4 leading upwardly from the pump and terminating in a spout 5. The spout 5 as well as the pump and throat are of the usual conventional construction and a detailed description thereof is not necessary. 85 In machines of this character it is necessary that the metal within the melting pot be maintained in a molten condition, and where gas works are accessible this is very easily 90 accomplished. However, when the linotype machines are placed in smaller towns it is necessary to use gasolene as a fuel for burners disposed beneath the mold and much difficulty has been encountered in providing a structure which will prevent the metal from 95 cooling prior to its discharge from the mouthpiece of the throat. It will, of course 100 be apparent that if the metal should become cooled before its passage from the crucible the outlet or mouthpiece will be clogged and the operation of the machine stopped.

To provide a structure overcoming these difficulties I dispose beneath the crucible a gasolene vapor burner of any conventional form being fed by a generator 7 disposed beneath the casing of the machine and supported thereby. A needle valve 8' controls

the supply from the generator and as the generator is of any approved type a description thereof will not be given. It will, however, be seen that the gasoline vapors introduced to the burner 8 will be ignited, and this burner consists of a conical cap 9 provided at its lower end with a series of small fuel openings, and the purpose of this burner is to maintain the metal in the crucible in a molten condition.

To prevent the metal from cooling during its passage through the throat of the crucible and prior to its discharge from the mouthpiece, I provide an auxiliary burner 9' positioned beneath the mouthpiece of the throat and fed by means of the vapor conducting pipe 10 attached to an opening in the upper end of the conical burner cap 9 and passing upwardly beneath the throat of the crucible to a point near the outer end thereof. The feeding pipe 10 then extends at right angles through an opening in the casing D and has at its free end a coupling member 11 attached thereto and provided with a cut off valve 12. To the coupling member is attached a joint 13 extending forwardly of the machine to a point near the outlet of the mouthpiece, and detachably connected to this joint is the small auxiliary burner 9' having a plurality of vapor outlets 15 therein which directly underlie the mouthpiece of the throat and extend entirely across the throat. The burner is supported at its free end by a plug 17 fitting therein and provided with an extension 18 engaging a socket within the casing surrounding the burner. While this is the preferred means for supporting the burner, it will, of course, be understood that any suitable supporting device may be used. From the foregoing, it will be observed that the vapors passing from the burner cap 9 will be conducted to the auxiliary burner by the pipe 10 which for the major portion of its length extends below the throat of the crucible and therefore the vapors passing to the auxiliary burner will never condensate as they are maintained in the proper condition by the heat passing from the throat of the crucible. The valve 13 is of any desired construction, its purpose being to control the amount of vapor permitted to pass to the auxiliary burner to produce a small and steady flame to prevent the metal from congealing prior to its discharge. With this type of burner the overheating of the various parts of the machine are eliminated as the flame is always small and steady.

The casing 1 surrounding the crucible is secured in place by the set screws 10', three being shown for the purpose of illustration, one of the set screws engaging a lug 19 projecting from the crucible while the other fastening screws are secured to the forward end of the melting pot as disclosed in Fig.

2. In order to preserve the heat within the crucible a packing of asbestos or other insulating material is disposed around the sides of the crucible between the surface thereof and the casing.

In a burner attachment of this character it is highly desirable that the auxiliary burner be in no way affected by the draft created by the main burner, and to this end the casing 1 carries near its forward end a web 22 closing the space between the lower portion of the throat 4 and the casing and supporting the burner 8 and the burner 9', so that the flame produced by the auxiliary burner will always be steady and is not subject to the draft created by the main burner and passing through the flue between the throat and the casing. While I have shown the web as being integral with the casing, it will, of course, be understood that the same may consist of any suitable separable partition that may be placed between the auxiliary and the main burner wherever desired.

While I have illustrated and described the preferred embodiment of the invention, I wish it to be understood that many changes in the sizes of the various elements and the arrangement thereof may be made without departing from the spirit of the invention.

Having thus described the invention, what I claim is:—

1. The combination with a casting pot, of a main burner disposed beneath said pot and having a burner cap, a jacket for the pot, a detachable mouthpiece burner located exteriorly of the jacket, a pipe connecting the main burner cap with said mouthpiece burner and extending for a portion of its way beneath the throat of the pot for conducting vapors to the auxiliary burner and a generator for feeding the main burner, substantially as described.

2. The combination with a casting pot, of a casing therefor, a main burner disposed beneath the casting pot, a generator for feeding said burner, a pipe extending from the main burner beneath the throat to a point near the mouthpiece and thence leading through the jacket, said portion disposed exteriorly of the jacket extending forwardly to a point beneath the mouthpiece of the crucible, and a burner connected with said portion and adapted to underlie the mouthpiece.

3. The combination with a casting pot, of a casing therefor, a main burner disposed beneath the casting pot, a generator for feeding said burner, a tube extending from the main burner beneath the throat to a point near the mouthpiece and thence leading through the jacket, said portion disposed exteriorly of the jacket extending forwardly to a point beneath the mouthpiece of the crucible, a burner connected with said

portion and adapted to underlie the mouth-piece, and a partition separating said main and auxiliary burners.

4. The combination with a casting pot, of
5 a main burner located beneath said pot, an auxiliary burner underlying the mouthpiece, a generator for the main burner, and fuel conducting connection between the auxiliary

burner and the main burner, and a partition separating said burners. 10

In testimony whereof I, affix my signature in the presence of a witness.

HANS PETERSEN.
